UNITED STATES PATENT OFFICE.

DAVID SWERDLOW, OF BROOKLYN, NEW YORK, ASSIGNOR TO SAFETY PIPE, INC., OF NEW YORK, N. Y., A CORPORATION OF NEW YORK.

PIPE.

Application filed September 25, 1924. Serial No. 739,751.

To all whom it may concern:

Be it known that I, DAVID SWERDLOW, a citizen of Russia, residing at 609 Hart St., Brooklyn, in the county of Kings, city and State of New York, have invented certain new and useful Improvements in Pipes, of which the following is a specification.

This invention relates to improvements in pipes and has particularly for its object the provision of a pipe of novel form which will effectively withstand the action of the wind and will remain lighted in all weathers.

A further object of the invention is the provision of a pipe particularly adapted for the use of automobile drivers.

Further objects of the invention will be apparent from the drawings, in which--

Figure 1 represents a side view in perspective of my improved pipe,

Figure 2 is a sectional view,

Figure 3 is a perspective of the three principal parts of the pipe,

Figure 4 is a sectional view along the line 4-4 of Figure 2, and

Figure 5 is a sectional view along the line 5-5 of Figure 2.

A represents what would be normally known as the bowl of the pipe having a central orifice B with additional air vents C and C' (see Figure 5). A metal collar is placed over the orifice B and the tobacco in the bowl A can be lighted by a match through the orifice B. Connected with the bowl A is a central portion of the pipe D having the metal collar E fitting into the neck of the bowl A. As shown in Figure 2, the intermediate portion of the body of the pipe D is contracted into the narrow drain F which serves to dispose of any particles of tobacco which may be blown into the body of the pipe D and also serves as a cooling chamber for the smoke issuing from the pipe. The drain F is held in position

in the body D by the metallic neck G as shown in Figure 2 bearing against a shoulder in the partition adjacent the bowl end of the member D at the base of the chamber

50. Into the body portion D is inserted the contracted tube M, terminating in the mouthpiece N. The stepped or reduced portion of the tube extended into the chamber or cavity of the mouthpiece serves to aid in forming a trap. In this pipe I have provided a simple construction of a pipe of 55 novel form which has adequate suction and which on account of its construction, can be easily taken apart and cleaned. No pipe cleaner is necessary in the continued operation of this pipe as it is merely necessary to 60 shake the pipe in order to get rid of any particles adhering to the bowl or auxiliary chamber.

Having fully described my invention, 65 what I claim is:

1. A cigar-shaped pipe embodying a bowl with a longitudinal orifice, a pipe body having a chamber provided with a transverse partition near its inner end and having an aperture and a shoulder, a metal collar in 70 the end of the body abutting against said shoulder, a drain tube extended through the aperture in said partition and having a flange bearing against said shoulder, and a mouthpiece in the other end of the body 75 having a contracted member extended into the chamber of the body.

2. A three piece cigar shaped pipe comprising a mouthpiece, a tobacco bowl and an intermediate section provided with a 80 trap, said trap-containing section having a perforated partition near the bowl end, a tube projecting therethrough and into the trap cavity, said tube provided with a flange to limit the entrance through the partition, 85 a collar connecting the trap section and the bowl, the bowl having a metal lined opening in its free end for lighting and draught purposes, the mouth piece having a tubular projection of reduced diameter projecting into 90 the trap cavity to cooperate with the tube projecting through the partition of the trap section.

In testimony whereof I hereunto affix my signature.

DAVID SWERDLOW.
